VALVE DEVICE HAVING PLUG-ACTUATED CHECK VALVE

Roy A. Bobo, Bartlesville, Okla., assignor to Phillips Petroleum Company, a corporation of Delaware

Application October 11, 1954, Serial No. 461,415

10 Claims. (Cl. 166—225)

This invention relates to an improved apparatus for running pipe or casing into a fluid-containing well bore. A specific aspect of the invention pertains to a casing fill collar or shoe provided with a back-flow valve and a plug-actuated check valve.

In running casing into a well bore containing drilling mud or other liquid, it is desirable to allow the liquid to enter the casing instead of running the inside of the casing dry. However, unless means are provided for controlling the flow of liquid into the casing as the casing is run, the drilling mud or other liquid will overflow the casing due to surges in pressure at the lower end of the casing caused by the movement of the casing downward through the drilling fluid and various flow control devices have been devised for use in the bottom of the casing as the same is being run in order to control the flow of fluid into the casing and avoid overflow from the casing at the surface. After the casing is run and the same has been landed, cement is forced down the casing thereby forcing drilling mud out of the casing and up the annulus between the casing and the walls of the bore hole into the mud pit through proper conduits connecting the annulus therewith. When the proper amount of cement has been pumped into the casing to provide the required amount of cementing or cement fill in the casing-bore hole annulus, a plug is inserted on top of the cement and drilling mud is pumped into the casing on top of the plug to force the cement down the casing and into the annulus surrounding the same. When the plug reaches a suitable obstruction in the bottom of the casing provided for this purpose, the flow of material into the casing is no longer possible and the proper amount of cement has been forced into the cementing area around the casing in the annulus surrounding the same. It is desirable to prevent back-flow of cement into the casing so that pressure on the fluid in the casing can be released.

An object of the invention is to provide an improved and novel valve device for use in running a well pipe such as a casing into a fluid-containing well bore. Another object of the invention is to provide an improved process for running a string of casing into a fluid-containing well bore and for running cement into the bore hole-casing annulus to cement the casing in. It is also an object of the invention to provide an improved valve device for running a casing into a fluid-filled well bore which permits maintaining a predetermined liquid-level in the casing at a substantial distance below the derrick floor. A further object is to provide an improved combination fill-up and cementing valve for use in running a well casing into a fluid-filled bore hole which permits operation with or without a choke. Another object is to provide a plug-actuated check valve in combination with a pressure differential valve for use in a shoe or collar in the lower end of a casing string to be run into a fluid-filled bore hole. Other objects of the invention will become apparent from a consideration of the accompanying disclosure.

The invention comprises an improved valve device com-

2

prising a pair of pressure release valves operating in opposite directions in a casing fill shoe or collar. The two valves in cooperation with their two valve seats form a single closure across the well casing. The back-flow valve is normally maintained in a closed position by means of a spring and the pressure is adjusted by the character of the spring and the length thereof to provide opening of the back-flow valve at a predetermined pressure differential in the fluid on opposite sides of the valve head thereby making it feasible to maintain the mud level in the well casing a predetermined short distance below the upper end of the casing or the derrick floor. The valve device of the invention can be utilized with or without a choke in the casing below said valve device. A choke is advantageous in minimizing the effect of surges in pressure in the well fluid at the bottom of the casing or fluid flow into the casing.

The upwardly closing valve in the valve device of the invention opens downwardly readily to permit fluid flow from the casing into the bore hole and into the annulus surrounding the casing. Upon locking of the downwardly closing valve in closed position by means of a latching device, fluid pressure tending to cause flow into the casing from the bore hole forces the upwardly closing valve into the closed position and can no longer open the downwardly closing valve because of the latching device which locks the same in closed position. This arrangement permits the flowing of cement from the casing into the bore hole and annulus surrounding the casing without permitting back-flow of the same into the casing when the pressure thereon is released. Hence, the upward closing valve of the valve device functions as a check valve in the casing when the plug following the cement into the casing contacts and actuates the valve latching mechanism.

A more complete understanding of the invention may be had from a consideration of the accompanying drawing in which like reference numerals are utilized to indicate corresponding parts of the various views and in which all views are schematic.

Figure 1 is an isometric view of a partial transverse vertical section of the valve device of the invention showing both valves closed.

Figure 2 is a transverse vertical partial section of another embodiment of the invention in which the check valve is a ball valve.

Figure 3 is a transverse vertical partial section of the valve device of the invention positioned in a casing shoe.

Figure 4 is a similar view to that of Figure 3 showing the valve device positioned in a collar.

Figure 5 is a similar view to Figure 4 showing a choke in the collar.

Figure 6 is transverse vertical view, partially in section, of well having the device of the invention positioned therein.

Referring to Figure 1, the valve device comprises a tubular valve body or housing 10 having threads 12 on the outside thereof for attachment to the inside of a collar or a shoe to be run with a casing in the lower section thereof. The lower end of the valve housing 10 is provided with a flapper valve 14, hinged with a spring hinge 16 of any suitable type which holds element 14 in closed position with only slight pressure. This upwardly closing flapper valve closes against seat 17 on the end of the valve housing, and also against valve head 18, providing a seat 20 therefor. Valve head 18 is attached by any suitable means to a valve stem 22 such as by threads 24. A valve guide 26 is rigidly attached by means of spider 28 to the inner wall of tubular member 10 so as to position valve stem 22 axially of the valve housing and provide support therefor. Valve stem 22 is provided with a series of radially extending wings

30 which form a shoulder or stop for the valve stem assembly and position valve head 18 against seat 20. Any suitable guide (not shown), such as a fixed key in valve guide 26 and a corresponding slot in valve stem 22, may be utilized to keep wings 30 aligned with supports 28. A helical spring 32 is positioned around the valve stem intermediate valve stem guide 26 and adjusting nut 34 which is utilized to change the force of the spring against valve head 18 and thereby regulate the differential pressure required to open valve member 18 and permit backflow of fluid into the tubing. A locking nut 36 locks adjusting nut 34 in position.

The upper section of tubular housing 10 is provided with a latching ring 38 having a series of longitudinal cut-away sections 40 which render the latching ring springable radially of tubular member 10. The outside wall of latching ring 38 is provided with a series of annular ridges 42 which have upper shoulders generally perpendicular to the wall of the ring. These annular ridges 42 are designed to slip over and lock with a series of annular ridges 43 on the inner wall of tubular member 10, the latter ridges having shoulders on the bottom side generally perpendicular to the wall of tubular member 10. Lugs 44 project radially from latching ring 38 and provide means for engaging a cementing plug forced down the well casing. Thus, when latching ring 38 is forced downwardly within tubular member 10, it is brought into contact or engagement with valve stem wings 30 and locks into position so as to prevent upward movement of the valve stem assembly and opening of the downwardly closing valve member 18. The lowermost ridge on the wall of tube 10 must be located so as to position the lower edge of ring 38 against wings 30. Hence, when latching ring 38 is locked against valve stem wings 30, fluid flow from the bore hole into the casing is prevented and the only flow permitted through the casing is from the casing into the bore hole through flapper valve 14 which now acts as a check valve to the flow of fluid into the casing.

Referring to Figure 2, the valve device illustrated therein is similar in most respects to that of Figure 1, the principal difference being in the arrangement of the valves in relation to each other and the structure involved in this relationship. Valve member 18 is provided with a seat 20 formed by flange 44, an inward extension of housing 10. Valve head 18 is annular in shape having an axial orifice or valve seat for upwardly-closing valve 46 which is in the form of a ball. A cage 48 serves to retain the ball in operative association with valve head 18 and the cooperating seat therein. Valve stem 22 is connected to valve head 18 by means of a spider. The valve device of this figure operates in substantially the same manner as the valve device of Figure 1, ball 46 functioning as a check valve to flow of fluid from the bore hole into the casing and as a flow valve during cementing of the casing wherein cement is flowed through the orifice in valve head 18 and out through cage 48. The latching ring 38 of Figure 1 is of course utilized in conjunction with the valve device of Figure 2.

Figure 3 shows the valve device 10 installed in a bottom shoe 50 by means of threads 12. Shoe 50 has a threaded upper section 52 and a nose section 54 having a passageway 56 for passage of fluid into and out of the shoe and casing. Nose section 54 is usually cast in place and retained by lugs 58. Threaded section 52 attaches directly to the lower end of a casing or pipe string.

Figure 4 shows the valve device 10 of the invention installed in a casing collar 60 by means of threads 12. The upper end of the collar has threads 62 adapted to attach to the end of a pipe string. Threads 64 on the lower end of the collar are adapted to attach the collar to another joint of pipe.

The device of Figure 5 is similar to that of Figure 4 but shows a choke 66 inserted in the lower end of the casing collar. Choke 66 has an orifice 68 and is threaded

into or otherwise attached to an adapter 67 which is attached directly to the collar.

Figure 6 shows a well bore having casings 60, 72, and 74 cemented in. This figure illustrates the positioning of the device of the invention in shoe 50 on the lower end of the casing string or, alternatively, in a casing collar 60 near the bottom of the string of casing. After the cement has been run into the annulus around the lower end of casing 70 and the same has set, the casing is perforated or the interior of the lower end of the casing, including the valve device of the invention, is drilled out and the drilling is continued into the cement and formation below the end of the casing in conventional manner in order to open up the casing for production. It is therefore essential that the interior elements of valve device 10 be constructed of drillable materials, which are well known in the art. Spring 32 can be made of bronze or other material which provides suitable tension and is drillable.

In operation, while pipe is being run, the downwardly-closing (pressure differential) valve and the upwardly-closing (flapper or ball) valve combine to prevent fluid entry into the pipe from below until a predetermined pressure differential has been established across the valve device. Once such pressure differential has been established across the valve device, the casing fills from below so long as sufficient pressure exists to hold the downwardly-closing valve open. The pressure differential required to open the valve from below is dependent upon the pressure exerted by the spring, which is adjustable by regulating the adjusting nut on the valve stem.

When the casing is properly positioned in the well it is cemented in place in the normal manner and the first cementing plug forces latching ring 38 downward, thus preventing upward movement of valve head 18 thus allowing the flapper valve of Figure 1 or the ball valve of Figure 2 to act as a check valve to prevent reverse flow of cement from the annulus into the casing.

Thus, the device functions as a differential pressure fill valve while the casing is being run but functions as a check valve after the first cementing plug reaches bottom.

Certain modifications of the invention will become apparent to those skilled in the art and the illustrative details disclosed are not to be construed as imposing unnecessary limitations on the invention.

I claim:

1. An improved valve device for use in a string of well pipe comprising an imperforate tubular member open at its ends and attachable to said pipe; a first valve seat across said tubular member fixed thereto; a first pressure release valve closing on said first valve seat; a second valve seat in said first valve disposed in the plane of said first valve seat when said first valve is closed; a second valve closing on said second valve seat, one of said valves being fluid pressure operable to permit upward flow thru said member and the other valve being fluid pressure operable to prevent upward flow and to permit downward flow thru said member; and means slidably engaging said tubular member and adapted to also engage said valve which permits upward flow thru said member to hold same in closed position.

2. The valve device of claim 1 wherein said first valve closes upwardly against said first valve seat and said second valve closes downwardly against the seat in said first valve and is engaged by said means.

3. The valve device of claim 1 wherein said first valve closes downwardly against said first valve seat and said means engages a valve stem on said first valve.

4. The device of claim 1 wherein said valve permitting upward flow thru said member is provided with a valve stem extending upwardly therefrom, a valve stem guide on said valve stem fixed relative to said member, a compressed spring around said valve stem between said guide and its valve biasing last said valve in its seat.

5. The device of claim 4 including a first spider fixing said valve stem guide to said member; a shoulder on the upper section of said stem engaging said guide and limiting the downward movement of said valve to its normally closed position; a second spider on the upper end of said stem extending out to a position adjacent the inner wall of said member above said first spider; and wherein said means comprises a locking ring ratcheted on the inner wall of said member and adapted to engage said second spider when moved downwardly to force said shoulder against said guide. 10

6. The valve device of claim 1 wherein said first valve comprises a flapper valve closing upwardly against said fixed valve seat.

7. The valve device of claim 1 wherein said first valve comprises a downwardly closing valve having a ball and cage on its under side extending thru said first valve seat, said ball seating upwardly in the valve seat in said first valve and functioning as said second valve. 15

8. An improved valve device for use in a string of well pipe comprising an imperforate tubular member open at its ends and attachable to said pipe string; a first valve seat across said member fixed thereto; a first pressure release valve closing on said first valve seat; a second valve seat in said first valve disposed in the plane of said first valve seat when said first valve is closed; a second valve closing on said second valve seat; an upwardly extending stem on one of said valves; a valve stem guide around said stem fixed to said member, said stem extending above said guide; and a shoulder on the upper end of said stem engageable with said guide to position its respective valve in said plane. 20 25 30

9. The device of claim 8 including holding means for forcing said valve stem downwardly to engage said shoulder with said guide and hold same in this position.

10. A differential casing-fill-device comprising a vertical imperforate tubular member adapted to be connected in the lower section of a casing string; an upwardly-closing valve and a cooperating fixed seat therefor across said tubular member adapted to open and close same to flow therethru from end to end; a downwardly-closing valve and a cooperating seat therefor within said upwardly-closing valve, the aforesaid valves and seats forming a single closure for said tubular member either of which operates to permit longitudinal flow thru said tubular member; means for holding said downwardly-closing valve closed under a predetermined pressure whereby same functions as a differential pressure valve permitting flow of fluid into said casing string from the lower end thereof; and means for latching said downwardly-closing valve in closed position whereby said upwardly-closing valve functions as a check-valve to prevent flow of fluid into said casing from the lower end thereof. 20
